UNITED STATES PATENT OFFICE.

CÉSAR JEAN MARIE LANCETTE, OF PARIS, FRANCE.

MONOLITHIC BUILDING.

Application filed May 21, 1920. Serial No. 383,164.

To all whom it may concern:

Be it known that I, CÉSAR JEAN MARIE LANCETTE, citizen of the Republic of France, and resident of Paris, Seine, France (post office address 74 Rue de Rivoli), have invented a new and useful Monolithic Building, which improvements are fully set forth in the following specification.

The present invention relates to the construction of permanent monolithic buildings, and it comprises various improvements hereinafter fully described.

According to the invention, there are utilized reinforced concrete columns, girders, panels etc., with or without ornamentation as desired, of the total height of each story of the building; and these elements, which have been previously moulded at the works, are joined together in a special manner during the construction of the building. Portions of the concrete are cut away during the molding for the purpose of exposing the ends of the reinforcing wires, which ends have previously been formed into loops or eyes. These eyes are arranged in juxtaposed relation, so that they may be fastened together by means of rods or pins which are inserted through them. In this way the various elements are securely connected to one another; and since the aforesaid wires extend in all directions, both vertically and horizontally, a homogeneous, monolithic building is thereby produced.

The same procedure is followed in building staircases, roofing framework, cupolas or domes and roofs, as well as pillars and lintels of doors and windows, with or without ornamentation, sills and balconies. In the last-named case, a single reinforced concrete unit will be moulded, comprising an entire bay with the dormer, sills and balcony slabs, the jambs of the dormer openings extending above the level of the upper story and offering the double advantage of forming the framework and pillars of the front walls. The aforesaid units, after having been removed from the moulds, but before the concrete has completely set, may be provided with iron fittings to receive the window frames and doors which are likewise constructed of reinforced concrete at the works.

In order to prevent any undue caving in of the members of the hollow front walls, and in order to render them better insulators as regards the outside temperature, a series

of cement or plaster battens of the width of the space between the wall members will be arranged, during the erection of the building, against the outer panel before the inner panel is put in position, the said battens resting on flat brackets, also of cement or plaster.

As regards the roofing, the same method is employed for manufacturing tiles having a special cross-section ensuring a tight joint and having a strength sufficient to dispense, in an advantageous and economical manner, with framework purlins, common rafters, battens and lathing, owing to the said tiles resting on the main rafters of the trusses, to which the said tiles will be secured.

The invention is also applicable to the construction of spouts, gutters, waste-pipes and the like; domes, cupolas, campaniles; spires; pillars, arches, walls and roofs of churches; sewers of small or large cross-section; pavements or flags of reinforced concrete; factory chimneys; bridges and bridge piers; retaining walls; the linings for tunnels, caves, shelters and, in general, any articles at present made of reinforced concrete, but with a greater degree of precision.

In the accompanying drawings:

Figure 1 is a fragmental sectional plan view of the ground floor of a building.

Fig. 2 is a detail view in horizontal section of the posts *a* of Fig. 1.

Fig. 3 is a similar detail of the posts *b*, Fig. 1.

Fig. 4 is a detail of the casing jambs *c* of Fig. 1.

Fig. 5 is a detail of the double posts or uprights *d* of Fig. 1.

Fig. 6 is a detail of the posts or uprights *e* of Fig. 1.

Fig. 7 is a detail of the hook connection of Fig. 6.

Fig. 8 is a vertical section on line C C of Fig. 1, with parts in side elevation.

Fig. 9 is a perspective view partly in vertical section on line B B of Fig. 1.

Fig. 10 is a transverse vertical section on line D D of Fig. 1.

Fig. 11 is a vertical detail section relating to part *g* of Fig. 8.

Fig. 12 is a vertical detail section relating to part *h* of Fig. 8.

Fig. 13 is a vertical detail section on line E E of Fig. 12.

Figs. 14 to 17 are vertical sections showing different details.

Figs. 18 and 19 are sectional perspective views of other details.

Fig. 20 is a sectional perspective view of a sewer construction.

5 Fig. 21 is a vertical section of a slightly modified form of sewer.

Fig. 22 is a vertical detail section relating to parts m' , n' , o' , l' of Fig. 20 and parts p' , q' , r' , s' of Fig. 21.

10 Fig. 23 is a horizontal section passing through lines F F and F' F' of Fig. 21.

Referring more particularly to the drawings, Figure 1 represents a portion of the ground floor of a house, showing the main 15 walls a and b and partitions c constituted by posts or uprights having junction wings or flanges for connection to double panels of reinforced concrete, the attachment being effected by hooking together the ends of the 20 reinforcing wires and then sealing the joints with cement, as indicated in broken lines disposed at an angle of 45° , this feature being shown more clearly on an enlarged scale in Figs. 2 to 6.

25 As indicated in said figures, the posts are approximately of H-section, and the reinforcing wires extend at opposite ends through their wings or flanges and are provided with terminal eyes or loops, through 30 which suitable connecting pins or wires are inserted; Fig. 7 representing such arrangement on a still larger scale. Figs. 5 and 6 show columns d and e of great strength, constructed by connecting together a plurality 35 of these flanged or winged posts which may be cut away to expose the reinforcing wires for the purpose of forming the eyes or loops above referred to, the posts also providing the mark rabbets. The empty spaces in the 40 said pillars can be filled up with concrete at the building yards, if it is desired to obtain a greater resistance to extra loads; and when it is question for instance of bridge piers, then in such cases care will be taken during 45 the moulding of the posts to leave projecting every 25 to 30 cm. in the direction of height, and every 10 to 15 cm. in the direction of width, round steel wires of 8 to 10 mm. occupying the whole width of the empty space 50 or hollow and terminating in hooks so as to form a reinforcement for the concrete core that will be cast.

It will be seen that in the case of those 55 posts only which are connected together by means of suitable wings, the mark rabbet, which will merely give the appearance of a stone joint, is situated in the hollow of the pillar, necessitating, on the spot and during the erecting, positive connection and sealing 60 on the two surfaces, the external or front one of which makes it necessary to effect a plastering joint; but this will not be the case for the posts on the front face when the latter, as at f in Fig. 1, has bays with spaced 65 piers, in which instance the mark rabbet

will always have to be in front so as to represent merely a stone joint, and the hooking of the wires and the sealing will be effected in the hollow of the wall before the positioning of the second inner panel which will have the mark rabbet necessarily concealed in the hollow of the wall, the hooking of the wires and the sealing being effected on the face seen from the interior of the house. For 70 making the partition walls, the mark rabbet (Fig. 2) will be concealed in the hollow of the wall, the hooking of the wires and the sealing being effected on the two faces seen from the interior. The posts of these walls will be spaced at variable distances apart 75 which can be as much as 3 meters, and the filling panels will be in a single piece corresponding in length to such distances, and of the total height of each story, being secured to the girders in the same manner, so that a 80 hooking of the reinforcing wires in every direction results, thus ensuring monolithic 85 construction.

Fig. 8 gives a general view of a building 90 with six stories and a ground floor, the view being partly in section taken vertically through the bays. It will be seen that the points of junction of the various elements of the floors and ceilings are indicated by 95 broken lines.

Fig. 9 is a vertical cross-section like Fig. 8, but passing through the entrance door on the ground floor and through the piers of all the stories, showing the double panels 100 of the front wall, which are in a single piece throughout the whole height of each story between the girders to which they are secured. Between the said panels which constitute a hollow wall, are interposed cement or plaster boards or battens resting on 105 flat brackets, also of cement or plaster, and superposed so as to form longitudinal cells about 50 cm. high, for the purpose of preventing any undue caving in of the wall members, as already stated.

Fig. 10 shows in transverse vertical section the hollow partition wall b (Fig. 1), which wall is constituted by panels of the total height of each story of the building. 110 These panels are connected together between girders moulded as above described and provided with joints which enable their connection to the horizontal floor and ceiling panels or slabs which rest moreover on hollow girders arranged about every two meters.

Fig. 11 is a vertical section illustrating the detail construction of the part g in Fig. 8, showing a balcony slab with a cornice, 115 forming a single element moulded in one piece with the hollow girder. The two wings or flanges of the girder are arranged so as to receive the floor and ceiling slabs and the lintel of the bay and the jambs which comprise in one and the same single 120 125 130

element the balcony floor, the dormer and the splays of reinforced concrete as already described, as well as the connection $t' t'$ such as it is obtained in moulding in order to 5 make possible the arrangement of the mark rabbet.

Fig. 12 is a detail section illustrating the small balcony and cornice indicated at h in Fig. 8; it has the same characteristic features as Fig. 11.

Fig. 13 illustrates on an enlarged scale the fastening or hooking together of the ends of the wires with eyes by means of a headed brad or pin; and the hooking together of the horizontal panel wires on the same principle, but by means of a rod, one end of which forms a stop hook, while the other passes through several eyes and can in its turn be secured by a cotter pin that 20 is inserted through a hole in the rod; said pin, however, will be unnecessary as the vertical arrangement of the rod will maintain it in position during the building operation until it is finally secured by the 25 cement joint.

Fig. 14 is a sectional view showing details of the above-mentioned rabbet, and also showing the cutting away to uncover or expose the eye ends of the juxtaposed 30 wires.

Fig. 15 is a detail of one of the vertical wall panels (or of the floor slabs), the cutting away of the panel (or slab) rendering visible the eye ends of the wires, through 35 the axis of which is passed a steel pin provided at one end with a stop head and secured at the other end by a cotter pin, as already described.

Fig. 16 is a view similar to Fig. 14 but 40 representing a slightly modified construction of the ends of the wire. One of the two moulded elements is provided with wires formed with double eyes, constituting a female member, while the wires of the 45 other element are provided at their ends with male members in the form of single eyes for engagement with the double eyes, as shown in Fig. 17. It will be seen that this modified construction enables the wires 50 to be arranged in the same axis, which is an advantage in the case of horizontal girders.

Fig. 18 illustrates the manner of joining or bonding the wall panels and the floor 55 and ceiling slabs. The bays form a one-piece, moulded element $a' b' c' d'$ comprising the bay, the casing, the dormer and the balcony slab (the latter being indicated in dotted lines so as to show the joining or 60 bonding.)

Fig. 19 is generally similar to Fig. 18, and represents the girders and the pillars constituting the frame work of the building, but omitting the panels with their 65 rabbeted and cut joints obtained during the

moulding. The bays form a one-piece, moulded element $a' b' c' d'$, and the girders g' carry junction elements for attachment of the girders h' . The pillars $e' f'$ carry at the upper part f' five junction branches, 70 four for connecting the horizontal girders, and the fifth for connecting the superposed vertical element.

Figs. 20 and 21 relate to the construction of a sewer according to the same method; 75 Fig. 20 showing the arrangement or bonding of the panels in four elements $m' l'$, $m' n'$, $n' o'$, $o' l'$, while Fig. 21 shows a generally similar arrangement of the panel elements $p' q'$, $p' r'$, $r' s'$, $s' q'$, and also 80 shows the formation of a strengthening rib.

Fig. 22 shows the joint between the adjacent edges of two of the panels represented in Figs. 20 and 21, and Fig. 23 shows in detail the strengthening rib which is also 85 represented in Fig. 21.

I claim as my invention:—

1. A monolithic building of one or more stories, comprising hollow vertical walls embodying pairs of spaced, reinforced concrete panels; vertical columns of reinforced concrete to which said panels are secured along their contiguous longitudinal edges; and horizontal girders of reinforced concrete to which said panels are secured at 90 their upper and lower ends; the panels of each story of the building extending the entire height of that story and having their reinforcements connected at their ends to the adjacent ends of the reinforcements of 100 contiguous columns and girders, so that the connected reinforcements extend in all directions.

2. A monolithic building of one or more stories, comprising hollow vertical walls embodying pairs of spaced, reinforced concrete panels; horizontal girders of reinforced concrete to which said panels are secured at their upper and lower ends, each panel of each story of the building extending the entire height of that story; and horizontal beams disposed at intervals within the spaces between the panels to divide them into longitudinal cells.

3. A monolithic building of one or more stories, comprising hollow vertical walls embodying pairs of spaced reinforced concrete panels; and horizontal walls embodying reinforced concrete girders having upper and lower flanges to which the lower and 120 upper ends of said panels are secured, and also having lateral flanges at opposite sides, and floor and ceiling slabs secured at their edges to the adjacent lateral flanges of contiguous girders; the panels of each story of 125 the building extending the entire height of that story.

4. In a monolithic structure, a pair of pre-formed concrete elements having metal reinforcing members embedded therein 130

which are formed at opposite ends with elongated eyelets, the members in one element being arranged approximately in end-wise alinement with those in the other element so that the eyelets on the confronting ends of said members will substantially register with each other, and a fastening member inserted through said registering eyelets, the confronting faces of concrete elements having portions thereof cut away to expose said eyelets and fastening members and permit their being fastened together; and a concrete filling in the space formed by said cut-away portions to bond the elements together.

5. In a monolithic structure, a pair of preformed concrete elements having metal reinforcing members embedded therein, and a rod disposed between the confronting faces

of said elements and to which the ends of the reinforcing members are connected, the said confronting faces of said concrete elements having portions thereof cut away to provide a space to receive said rod and to permit its connection with the reinforcing members; the parts of the cut-away faces at one side of said rod registering with each other, and the parts at the opposite side being flared away from each other and roughened; and a concrete filling in said space to bond the elements together.

In testimony whereof I have signed this specification in the presence of a subscribing witness.

CÉSAR JEAN MARIE LANCETTE.

Witness:

ALPHONSE NICOLS.
